3 Claims. (Cl. 36—22)

1

The present invention relates to shoes of an improved construction and to an improved method of making shoes.

The primary object of the present invention is to simplify the art of shoe making and to reduce the cost of labor and material. More particularly, pursuant to this object of the invention the shoe is made in such a way as to enable the upper and the insole to be assembled in an improved manner without requiring a lasting operation and to facilitate the securing of the upper and insole to each other. A last or form may be, and preferably is, inserted in the shoe after the upper and insole are secured to each other, whereby to facilitate the attachment of the outsole and the usual shoe finishing operations.

More specifically, it is an object of the present invention to provide an insole which is cut in such a way that it can be manipulated so as to present successive marginal edge portions along a substantially straight line to the marginal edge of the upper during the operation of stitching the insole and upper to each other.

In accordance with the present invention, both of the insole and the upper are each cut to the size and shape they are to have, respectively in the finished shoe; and the insole is additionally cut in certain portions thereof, as will subsequently be described in detail; and thereafter the insole and the upper are stitched together.

Another object of the present invention is the provision of a shoe of improved construction, in which the upper and insole are secured together without the formation of wrinkles and bulges and without a lasting operation.

The invention may be embodied and practiced in various ways including but not limited to those hereinafter referred to by way of illustration but without limitation, and the above and other objects, features and advantages of the invention will be fully understood from the following description considered in connection with the accompanying illustrative drawings.

In the drawings:

Fig. 1 is a side view in elevation, of a shoe made according to the present invention;

Fig. 2 is a perspective view of the underside of an insole constructed according to the present invention, parts being cut away for purposes of illustration;

Fig. 3 is a perspective view of the upper side of the insole, a portion being shown displaced to show a structural feature;

2

Fig. 4 is a sectional view taken on the line 4—4 of Fig. 2;

Fig. 5 is a perspective view of the insole of Fig. 2 shown in an opened annular position; to facilitate the operation of stitching the insole and upper to each other;

Fig. 6 is a perspective view of the upper joined to the insole;

Fig. 7 is a sectional view taken on the line 7—7 of Fig. 6;

Fig. 8 is a view similar to Fig. 7 showing a welt secured to the upper and insole; and

Fig. 9 is a view similar to Fig. 7 showing the upper of the shoe secured to the insole at the top of the latter.

Referring to the drawings and more particularly to Figs. 1 through 4 thereof, the shoe 10 formed according to the present invention comprises an upper 12, an insole 14, an outsole 16 and a heel 18. According to the method of the present invention the upper 12 and insole 14 are cut to the size and shape they are to have in the finished shoe and are secured to each other off the last; i. e., they are attached to each other without the usual lasting operation. Pursuant to the present invention, the insole is prepared in the manner which will now be described.

Insole 14 is provided with a bevelled cut 18 which extends for substantially the full length of the insole 14 medially thereof in one part of the thickness of the insole but which terminates short of the ends 20 and 22 of said insole in the other part of the thickness of the insole, so that said insole is divided longitudinally but remains connected at its end portions. (See Figs. 3 and 5.) The longitudinal cut 18 comprises complementary bevelled edge portions 24 and 26 which are adapted to be secured together in lap joint fashion after the upper 12 and insole 14 have been secured to each other as will be described in detail hereinafter. The insole 14 is transversely cut at the toe and heel portions 27 and 29, respectively, at 28 and 30, respectively, with a bevelled cut which extends from both extremities of the longitudinal cut 18 and at both sides of said longitudinal cut. More specifically, the toe and heel portions of the insole are cut in planes lying between the planes of the top and bottom surfaces of the insole, said planar cuts being at an angle to said surfaces of the insole. Preferably the transverse cuts 28 and 30 at the ends 20 and 22, respectively, of the insole 14 are arcuate, conforming to the arcuate end edges 11 and 13, respectively, of the adjacent ends of the insole. It will thus be seen,

therefore, that the transverse cuts 28 and 30 are substantially parallel to their associated end edges 11 and 13, respectively, of the insole 14 at the ends 20 and 22, respectively. The transverse arcuate cuts 28 and 30 divide the toe and heel portions 27 and 29, respectively, in between opposite surfaces 31 and 33 thereof, and one of said divided parts of each of said toe and heel portions, namely the bevelled outer marginal edge portions 32 and 34, respectively, are radially slit in a manner to be described in detail hereinafter.

The marginal edge portions 32 and 34 are radially slit at 35 to form a plurality of spaced radially extending portions 36 (see Fig. 5), said slits extending transversely of the outer marginal edge portions 32 and 34 for substantially the full width thereof but terminate short of outer marginal edge portions 37 and 39. Thus the outer marginal edge portions 32 and 34 are radially slit at 35, which slits extend radially from the inner edges 38 and 40 of the outer marginal edge portions 32 and 34, respectively. Thus the toe and heel portions 27 and 29, respectively, are divided in a plane of division lying generally between the opposite surfaces of the insole so that the toe portion 27 has superposed portions 32 and 33 and the heel portion 29 has superposed portions 34 and 37. The superposed portions 32, 33, and 34, 37 are separable from each other at the plane of division, and the superposed portions at outer marginal edge portions 32 and 34 are radially slit in the manner aforescribed whereas the superposed portions 33 and 37 each have two separate parts, namely the parts 41, 43, and 45, 47, respectively. It will be noted that the parts 41, 45, and the parts 43, 47 are on opposite sides of the longitudinal cut 18. As shown in Figs. 2 and 3, the separable pairs of parts 41 and 43 at one end of the insole, and parts 45 and 47 at the opposite end, have edge portions extending from one end of the insole toward the opposite end and outwardly of the longitudinal median line 18. Also, the edge portions of the separable parts of each pair extend toward each other and outwardly of said longitudinal line.

With the insole 14 cut and slit as aforescribed, said insole is adapted to be opened and manipulated as shown in Fig. 5, to a substantially annular form. With the insole 14 so opened and manipulated as shown in Fig. 5, it is adapted to be secured to the upper 12, the lower marginal edge portions 42 of the upper 12 being adapted to be secured to the outer marginal edge portions 44 of the insole 14. With reference to Fig. 5 it will be seen that when the insole 14 is opened the outer marginal edge portions 32 and 34 may be substantially straightened out so that the outer marginal edge portions 44 of the insole 14 may be secured to the lower marginal edge portions 42 of the upper 12 with said edge portions being flatwise positioned. Thus the marginal edges 42 of the upper and the marginal edges 44 of the insole are fed flatwise in successive increments and in superposed relationship to the work support of a conventional sewing machine or other securing means with said edges being substantially parallel. In the preferred embodiments, as illustrated in Figs. 6-9 of the drawing, the marginal edges of the insole are stitched to the marginal edges of the upper by a line of stitching 21 but it will be readily apparent that any other suitable securing means may be utilized, for example, gluing or pasting, or stitching in conjunction with gluing or pasting.

After the marginal edges 42 of the upper are stitched to the marginal edges 44 of the insole, the insole 14 is restored to its original form, that is the form prior to the aforescribed cutting and slitting operations. In the preferred embodiment the insole 14 is restored to its original form by means of cementing the complementary cut edge portions to each other but it will be understood that said restoration may be effected by other means, for example, stitching, or stitching and pasting, or cementing. Thus the complementary bevelled edge portions 24 and 26 of the longitudinal cut 18 are pasted to each other to form a lap joint and the outer marginal edge portions or outer divided portions 32 and 34 are pasted to their associated inner divided or bevelled edge portions 46 and 48, respectively, in lap joint fashion to form the upper and insole assembly 50 shown in Figs. 6 and 7. Thereafter an outsole 16 may be secured to the upper and insole assembly 50 in any conventional manner and the usual shoe finishing operations performed to form the finished shoe 10 shown in Fig. 1.

The lower marginal edge portions 42 of the upper 12 may be secured on the outside of the outer marginal edge portions 44 of the insole 14 as shown in Figs. 6 and 7, or, as shown in Fig. 9, the lower marginal edge portions 42' of the upper may be secured on the inside of the outer marginal edge portions 44' of the insole. It will be understood that in the embodiment shown in Fig. 9 the upper and insole assembly 50' is formed according to the method aforescribed with reference to Figs. 2 to 7 except the marginal edge portions 42' of the upper is secured on the inside of the marginal edge portions 44' of the insole.

With reference to Fig. 8, if desired, a welt 52 may be secured to the insole 14 and upper 12 at the same time the insole is secured to the upper in the manner aforescribed. Thus welt 52 may have its marginal edge portion 54 secured to the marginal edge portions 42 and 44 of the upper and insole, respectively, at the time the marginal edges 42 and 44 are secured to each other in flatwise condition. The marginal edge portions 54 of the welt 52 may thus be secured to the marginal edges of the upper 12 and insole 14 and if desired said securing may be performed by the same line of stitching 21' which secures the marginal edge portions of the upper and insole to each other. Thereafter a suitable outsole 16' may be secured to the welt 52 in any conventional manner and the usual shoe finishing operations performed.

After the insole and upper are secured to each other in the manner aforescribed a form or last may be inserted in the assembly to facilitate the attachment of outsole 16 and the usual shoe finishing operations. The radially split outer bevelled portions or marginal edge portions 32 and 34 of insole 14 permit such portions to be straightened out so that the marginal edge 42 of the upper may be secured to the marginal edge 44 of the insole without the formation of wrinkles or bulges and without a lasting operation, to thereby form a high quality securing. Thus the aforescribed radially slit portion allows the periphery of the toe and heel portions 27 and 29, respectively, to be straightened out so that the outer peripheral marginal edges 44 of the insole can be secured to the lower peripheral marginal edges 42 of the upper with said marginal edges being held parallel and flatwise in successive increments. In the case of a shoe having a welt such as shown in Fig. 8 the instant invention permits

the welt to be secured to the insole and upper at the same time the insole is secured to the upper in the manner aforescribed. The above described method of securing the upper 12 to the insole 14 is relatively inexpensive, requires a minimum of time and produces an eminently superior product.

While I have shown and described the preferred embodiment of my invention, it will be understood that various changes may be made in the present invention without departing from the underlying idea or principles of the invention within the scope of the appended claims.

Having thus described my invention, what I claim and desire to secure by Letters Patent is:

1. An insole for a shoe, said insole having the size and shape it is to have in the finished shoe, said insole being divided along a longitudinal line disposed substantially midway of the width of said insole and with one end of said dividing line terminating near but short of at least one end of said insole, said insole further being divided at an end portion adjacent said end in a plane of division lying generally between the opposite surfaces of the insole so that said end portion has superposed portions which are separable from each other at said plane of division, one of said superposed portions having two separable parts at opposite sides of said longitudinal line and the other of said portions having an undivided marginal edge at the adjacent edge portion of said insole, said one of said superposed portions having edge portions extending from said end towards an opposite end and outwardly of said longitudinal line.

2. An insole for a shoe, said insole having the size and shape it is to have in the finished shoe, said insole being divided along a longitudinal line disposed substantially midway of the width of said insole and with both ends of said dividing line terminating near but short of the ends of said insole, said insole further being divided at both end portions adjacent said both ends in a plane of division lying generally between the opposite surfaces of the insole so that each of said end portions has superposed portions which are separable from each other at said plane of division, one of said superposed portions having two sepa-

rable parts at opposite sides of said longitudinal line and the other of said portions having an undivided marginal edge at the adjacent edge portion of said insole, said one of said superposed portions at each end of said insole having edge portions extending towards each other and outwardly of said longitudinal line.

3. An insole for a shoe, said insole having the size and shape it is to have in the finished shoe, 10 said insole being divided along a longitudinal line disposed substantially midway of the width of said insole and with both ends of said dividing line terminating near but short of the ends of said insole, said insole further being divided at both end portions adjacent said both ends in a plane of division lying generally between the opposite surfaces of the insole so that each of said end portions has superposed portions which are separable from each other at said plane of division, 20 one of said superposed portions having two separable parts at opposite sides of said longitudinal line and the other of said portions having an undivided marginal edge at the adjacent edge portion of said insole, said insole being divided along said longitudinal line and further divided at said end portions by a bevelled cut, said other portions having a plurality of radial slits whereby said last mentioned portions may be disposed along a generally straight line, and 25 said one of said superposed portions at each end of said insole having edge portions extending towards each other and outwardly of said longitudinal line.

ANDRÉ PERUGIA.
